UNITED STATES PATENT OFFICE.

LEHMAN V. HOWARD, OF NEW BRIGHTON, PENNSYLVANIA.

REGENERATOR AND LIKE STRUCTURE.

Application filed September 30, 1922. Serial No. 591,672.

To all whom it may concern:

Be it known that LEHMAN V. HOWARD, residing at New Brighton, in the county of Beaver and State of Pennsylvania, a citizen 5 of the United States, have invented or discovered certain new and useful Improvements in Regenerators and like Structures, of which improvements the following is a specification.

10 My invention relates to improvements in the structure of checkerwork, built within the chambers of regenerators, recuperators, and such like apparatus. In an open-hearth steel furnace, for example, the regenerator is 15 a piece of auxiliary apparatus. It is a chamber filled with bricks laid dry in superposed tiers or layers, and with wide intervals between adjacent bricks. The whole constitutes a heat absorbing and heat emitting 20 body, through which a stream of gas may find greatly subdivided and devious passage. In operation, streams of hot gases escaping from the furnace chamber and of fuel gas (or of air) approaching the furnace chamber, alternately flow through. The hot gases 25 as they flow through raise the checkerwork to high temperature, and when in sequence the flow of hot gases is cut off and fuel gas (or air) on its way to the furnace is caused 30 to pass through instead, that stream of fuel gas (or air) is heated preparatory to combustion.

As regenerators (and recuperators) continue in service they deteriorate and rapidly 35 lose efficiency; they become clogged with cinders and brick dust; the hot gases from the furnace chamber, still more or less in flaming condition, and bearing solid particles, erode the bricks, and even soften and 40 melt them and cause their substance to run; explosions of gas shatter the bricks. In such various ways the checkerwork becomes fouled and the free flow of the gaseous streams is obstructed. The regenerator has 45 then to be put out of commission, and opened, and the checkerwork has to be removed, the refuse cleaned out, and the whole rebuilt.

50 My invention consists in a structure which admits of cleaning without disturbance, and of removal and replacement of parts without complete tearing down and rebuilding, and a structure which, furthermore, is resistant to deteriorating influence.

55 In the accompanying drawings, Fig. I is a view in vertical section through the regener-

ators of an open-hearth furnace in which my invention has been embodied. Here are shown two regenerator chambers, one for the gas (on the left), one for the air (on the 60 right). They differ, so far as I am now concerned, in size only, and my invention is applicable equally to both. It will be understood that in the course of furnace operation both chambers are at one time swept by 65 streams of hot gases, and then in turn are parts of the separate conductors, through which fuel gas and air approach the furnace.

Fig. II is a fragmentary view in vertical 70 section, on a plane at right angles to that of Fig. I, and may be understood to be a section through either of the two regenerators of Fig. I. Fig. III, drawn to larger scale, shows in side elevation and in plan a brick 75 of the particular shape employed in the practice of my invention. Fig. IV is a view in longitudinal section, and drawn to still larger scale, of the support which I employ for the bricks within the chamber. 80

The bricks 1 are not stacked within the chamber, tier upon tier, as is usual, but are strung upon metal, rod-like supports, preferably in the form of pipes 2, which supports are at opposite ends carried by the opposite 85 chamber walls. The bricks are preferably strung upon the support in face-to-face abutment, brick upon brick, and they fill all the space from wall to wall. To achieve such an assembly, the bricks are perforate, as 90 shown in Fig. III. Preferably they are provided in their abutting faces with interlocking tongues and grooves, and in assembly the terminal bricks of each string may be built into the opposite chamber walls. This is indicated in exemplary manner at 20. Thus alignment of the bricks within the string may be maintained, and rigidity of the structure as a whole increased. The assembly will be understood on comparing Figs. I, II 100 and III. The chamber is choked or obstructed with an assembly of cross bars of refractory material extending from wall to opposite wall, the bars being sustained by the walls and independently each of the others. 105

In assembly, each string of bricks is continuous from wall to wall; each stands spaced apart from adjacent strings, both laterally and vertically. No string carries the weight of superposed bricks. 110

The particular arrangement or grouping of the strings of brick within the chamber

may be varied. I prefer the arrangement shown, in which the strings are arranged in horizontal rows, while vertically the strings of the successive rows are arranged in staggered succession.

The strings of bricks are supported by two opposite walls of the chamber. The other two walls are built, one or both of them, with blind arches 3. When after continued service the efficiency of the regenerator is in appreciable degree impaired, the curtain walls within these arches (or one of them) may be removed. Scrapers may then be introduced and dust and cinders deposited upon the bricks or collected on the floor of the chamber may be removed. It will be remarked that such cleaning is quite impossible with ordinary checkerwork, for in it there are no free spaces extending through the whole body of brickwork, either horizontally or vertically.

When a regenerator has so been opened, and cleaned, if cleaning be necessary, inspection will reveal any defects which may have developed in any particular string of bricks. That string, if there be such, may be individually removed, by tearing out so much of the opposite supporting walls as may be necessary, but no more, and repair and replacement may then follow. The screen walls will then be replaced and the regenerator will be put in service again. In view of this and in distinction from the usual regenerator, my improved structure may be characterized as being semi-permanent.

I have said of the supports for the bricks that they preferably are in the form of pipes 2, and in Figs. I and IV, I show these pipes built and arranged for the circulation of water through them. Any preferred arrangement to this end may be employed; I show circulation pipes of Field type, in which circulation is had through concentric passageways, and this is the structure which I prefer.

The purpose of water cooling is to maintain the pipes rigid, and to prevent them from sagging after prolonged exposure to intense heat. It will of course be true that the flowing water will carry heat away, and to that extent will diminish the heat transference primarily in view. But this diminution is relatively small; of course, the temperature and quantity of the circulating water will be such as to accomplish the end described, and no more; and I find that the large gains, the nature of which I have indicated, vastly exceed the small loss in heat dissipation. Instead of water, air may be employed, or even steam, to flow through the pipes 2 and keep their temperature below the point of undue softening. The particular fluid employed will depend on circumstances and on temperature conditions.

It may be found desirable, particularly in large chambers, to support the strings of bricks vertically at a point or points intermediate their length, and in such case auxiliary supporting walls such as that indicated at 4, Fig. I, may be built up as the regenerator is built. This wall may, if opposite sides of the chambers are externally accessible, constitute the inner anchorage and resting place for two opposite strings of bricks, or it may, as indicated in Fig. I, be an intermediate support for strings of brick which extend in continuity from wall to wall of the regenerator chamber; and in that case, removal of any one string will involve more or less complete removal of this supporting wall.

I have described my invention in its application to regenerators of open-hearth furnaces. As clearly indicated at the beginning, it is applicable to checkerwork built in a chamber, whatever be the association in which it is used.

I claim as my invention:

1. A preheater for gaseous substance which consists of a chamber with entrance and exit for a gaseous stream, the space within said chamber being obstructed by a plurality of cross bars of refractory material, each bar independently supported by opposite chamber walls.

2. A preheater for gaseous substance which consists of a chamber with entrance and exit for a gaseous stream, a plurality of rod-like supports extending across the chamber from wall to wall, and a body of refractory material enveloping and carried by each rod-like support.

3. A preheater for gaseous substance which consists of a chamber with entrance and exit for a gaseous stream, a plurality of rod-like supports extending across the chamber from wall to wall, and a series of interlocked bricks strung upon and enveloping each rod-like support.

4. A preheater for gaseous substances which consists of a chamber with entrance and exit for a gaseous stream, a plurality of internally cooled supports extending from wall to wall within the chamber, and a body of refractory material enveloping and carried by each support.

5. A preheater for gaseous substance which consists of a chamber with entrance and exit for a gaseous stream, a plurality of pipes extending across the chamber from wall to wall, a body of refractory material enveloping and carried by each pipe, and means for effecting circulation of a cooling fluid in said pipes.

6. In a regenerator or like structure, the combination, with the regenerator chamber, of a plurality of individually independent bars of refractory material extending horizontally across the chamber and arranged in

a vertical succession of horizontally extending rows, the bars of the successive rows arranged in staggered relation to one another.

7. In a regenerator or like structure, the combination with the regenerator chamber of a plurality of individually independent cross bars of refractory material extending between opposite chamber walls, one of the

other chamber walls being built with a blind arch filled with a screen wall. ¹⁰

In testimony whereof I have hereunto set my hand.

LEHMAN V. HOWARD.
